United States Patent Office.

L. F. HENDERSON, OF FREEPORT, ILLINOIS.

Letters Patent No. 73,098, dated January 7, 1868.

IMPROVEMENT IN PORTABLE FENCES.

The Schedule referred to in these Letters Patent and making part of the same.

TO ALL WHOM IT MAY CONCERN:

Be it known that I, L. F. HENDERSON, of Freeport, in the county of Stephenson, in the State of Illinois, have invented an Improved Portable Fence; and I do hereby declare that the following is a full and exact description thereof, reference being had to the accompanying drawings, and to the letters of reference marked thereon, making a part of this specification, in which—

Figure 1 is an elevation of two lengths of my fence.

Figure 2, an end elevation of the same.

Figure 3, a plan view of one of the uprights, showing how the top rails are locked into it.

Figure 4, a perspective representation of the top rail.

Figure 5, a representation of one of the lower rails.

This invention relates to a new method of constructing a light, cheap, and substantial fence, which can be readily put up and taken down by any person having sufficient skill to build a common farm-fence.

In order to give a correct understanding of my invention, I have marked corresponding parts with similar letters, and will now give a detailed description.

A represent the uprights of the fence, which are made of common fence-boards, sawn diagonally through, so that a single board, when so cut, will make both parts of an upright having a narrow top and a broad base, as seen at fig. 2. The upright is then fastened together by cleats, F, also made of strips of boards and wrought nails, and is then made fast to a base-board, B, also with nails. This being done, the upright is ready to be put in the fence. The top rails D D have projections E E, made of short pieces of boards, fastened to their ends by nails, for the purpose of locking over the uprights A, as seen at fig. 3, there being a space between the parts A A, of sufficient size to permit the boards to pass each other and rest on the upper cleat F. The boards G have projections I secured to their ends, similar to those at E, and used to prevent said boards from slipping out of place. The base, B, should be cut from fencing, and have inclined ends, as seen at fig. 2, in order that the stakes C, also made of fencing, may be driven in the ground, shown at X, and hold the uprights in position.

Operation.

One upright should first be secured, after which the lower rails G can be put in at one end, and the other end adjusted before the opposite upright is secured to the top rails D, completing the panels. When an angle is to be made in the fence, the rails can be nailed to one of the uprights.

Having thus described my invention, I claim, and desire to secure by Letters Patent—

The uprights A A, secured with cleats F F, and to bases B B, in combination with top rails D, stakes C, and lower rails G, substantially as and for the purpose set forth.
